UNITED STATES PATENT OFFICE

2,035,501

SILENCER

Sidney Oldberg, Detroit, Mich.

Application June 17, 1935, Serial No. 27,062

1 Claim. (Cl. 137—160)

This application relates to silencers and more particularly to silencers of the sound wave attenuating type.

The principal object of the present invention is to provide a silencer wherein the exhaust gases travel in a straight line through the silencer with no baffle or deflection and wherein the silencer, though composed of but three shells with no intermediate longitudinal barriers, will provide two separate resonator chambers for the silencer; and it is also an object, in the construction of such a silencer, to rigidify the entire construction so as to eliminate undesirable characteristics.

Other objects of the invention will be readily understood and appreciated upon reference to the following detailed description of an embodiment of the same and upon reference to the appended drawing, whose

Fig. 1 shows an embodiment in longitudinal section; and whose

Fig. 2 is a transverse section on line 2—2 of Fig. 1.

Referring to the drawing, it will be seen that there is shown a silencer including a plurality of relatively telescoped shells 10, 11, and 12 having open ends closed by end headers 14 and 15.

The inner shell is open from header to header to provide a through passage for exhaust gases and is covered with a plurality of minute closely spaced perforations 16 which provide a communication between the interior of the inner shell and the space between the inner and interme-

diate shells, which space contains a series of conical diaphragms 17.

The intermediate shell is provided with large openings 18 and 19 which provide communication between the interior of the intermediate shell and the relatively isolated spaces 20 between the intermediate and the outer shell. 5

These spaces are isolated by virtue of the engagement between the intermediate shell and the outer shell, which is oval, at the diametrically opposed tangential lines 21, and such engagement, in addition to providing two relatively isolated resonator chambers 20, also tends to rigidify the silencer by virtue of the fact that the intermediate shell acts as a strut between opposed 15 sides of the oval outer shell, which strut is reinforced by the diaphragms and the inner shell.

Now having described the invention and a preferred embodiment of the same, reference will be had to the claim which follows for a determination of the scope of the invention. 20

I claim:

In a silencer, an outer shell of substantially oval cross section having broad sides and narrow edges, a shell of substantially circular cross section disposed therein and connecting the opposed broad sides of the outer shell and dividing the interior of the latter into two relatively isolated spaces, each opposite portion of the inner shell having a hole which communicates the interior 30 of the inner shell with each of these spaces.

SIDNEY OLDBERG.
